UNITED STATES PATENT OFFICE.

FERDINAND A. RUDOLF, OF JAMAICA, NEW YORK, ASSIGNOR TO GERALD M. LIVINGSTON, TRUSTEE.

MANUFACTURE OF NITROGEN.

Application filed October 15, 1920. Serial No. 417,254.

To all whom it may concern:

Be it known that I, FERDINAND A. RUDOLF, a citizen of the United States, residing at Jamaica, Long Island, in the county of Queens and State of New York, have invented certain new and useful Improvements in the Manufacture of Nitrogen, of which the following is a specification, reference being had therein to the accompanying drawing.

My invention relates to improvements in the recovery of nitrogen from a mixture which may be rich in nitrogen and containing carbon monoxide, carbon dioxide, small amounts of hydrocarbon, and practically no oxygen evolved from certain types of gas producers and hydrocarbon generators. This mixture of gases may analyze 60% or more of nitrogen, the major portion 20 of the rest of the mixture being carbon monoxide with varying percentages of the other gases mentioned. Oxygen as a free gas is entirely absent, or present in only small quantities. The invention is applicable to processes where comparatively pure nitrogen is required and where the carbon monoxide content of the gas is not sufficiently high to render the gas valuable as a fuel.

30 In the accompanying drawings, I have illustrated a suitable form of apparatus such as may be employed in the practice of the invention, the same being illustrated in longitudinal section, parts being broken 35 way.

Referring to said drawing, 1 indicates the reaction chamber which may be of cast iron suitably supported and which is filled with the reacting oxide preferably in granular form. This chamber preferably comprises three sections numbered respectively 2, 3 and 4, and the oxide in the chamber indicated by the reference character 2 when once reduced is not again regenerated but 45 is used in the reduced form as a precaution against accidental introduction of oxygen. 3 indicates the actual reaction chamber wherein the oxidation of carbon monoxide to carbon dioxide takes place. The final 50 section 4 is intended as a precaution for the final clean-up of carbon monoxide. There are no partitions of any kind between these several sections. 5 is the combustion chamber and 6 a boiler, heat economizer, heat exchanger, or reaction chamber for

maintaining the heats of reaction in any step of any process and these tubes may be located either above or below the reaction chamber 1. The fuel for the combustion chamber 5 is in the form of a gas mixture 60 (CO—N) and air, the former entering by way of the pipe 7 controlled by the valve 8, and the air by the pipe 9 controlled by the valve 10. The gases from the combustion chamber 5 passes upwardly around the 65 reaction chamber 1, between the tubes 6 and out by way of the pipe 11 controlled by the damper 12, or providing the damper 13 is open these gases may pass to the atmosphere by way of the pipe 14. From 70 the reaction chamber 1 the gases may escape to a gas washer and gasometer (not shown) subject to the control of the valve 15 upon pipe 16, or the regenerative gases may escape to the atmosphere through the 75 pipe 17 controlled by the valve 18. Air may also be admitted to the reaction chamber 1 by way of the pipe 19 controlled by the valve 20.

The mixture of carbon monoxide and 80 nitrogen is obtained from any suitable source such as a gas producer or hydrocarbon generator wherein a mixture of carbon monoxide and nitrogen is produced and the hydrocarbons have been condensed out. 85 For the purpose of illustration I will assume a gas mixture containing about 65% nitrogen and 35% carbon monoxide. This gas enters through the pipe 7 and is mixed with a regulated amount of air from the pipe 9, the mixture being ignited at the burner 21 in the chamber 5, the mixture being so regulated that the products of combustion will contain some carbon monoxide (not over 10% and preferably not 95 under 5% as a matter of insurance.) For purposes of insurance against unnecessary introduction of oxygen into the combustion chamber through the walls, etc., the pressure in the chamber is maintained slightly 90 above that of the surrounding atmosphere by means of suitable fans and exhausters not shown.

The reaction chamber being fully charged with metallic oxide, preferably iron (ferric oxide) or copper oxide in granular form, the products of combustion controlled by the valve 12 now pass through this mass within the reaction chamber 1 and during any step of the process or preparatory to 105 110

operation or during regeneration of the oxide these gases may be exhausted through the outlet 17 to the atmosphere, but during regular operation they pass through the pipe 16 to a suitable gas washer and gasometer, the valve 18 being of course closed. After the metallic oxide in the reaction chamber 2 is once reduced, no attempt is made to regenerate it and it is preferably maintained in its metallic state in order to absorb any oxygen which might get into the system due to carelessness in handling. In the reaction section 3 any of the following reactions may take place:

or when copper oxide is used

20 In lieu of the metals designated, any other easily reducible oxide of a metal may be used. The last reaction section 4 is so controlled that very little oxide enters into reaction there. Its purpose is insurance against the passage of carbon monoxide gases into the gasometer. After reaction has progressed so that the major portion of the oxides in the second section 3 shall have been reduced, which may be predetermined by any suitable method, the combustion of the gases is stopped in the combustion chamber 5. Valves 8, 10, and 15 are closed and valves 13, 20 and 18 are opened. Air is now permitted to enter through the pipe 19 and passes through the reduced metallic particles in the central section 3 and re-oxidizes them to the higher oxides. Care should be exercised as at this point the reaction chamber may become overheated as in the fine state of subdivision the metallics rapidly absorb oxygen and will create intense heat.

After regeneration has been completed, valves 13 and 20 are again closed and valves 12, 10 and 8 are opened in the order named, and the reduction process is again resumed, passing the initial gases out by way of the pipe 17 until the apparatus shall have been cleaned of any remaining oxygen from the regeneration step of the process. Valves 15 and 18 are then respectively opened and closed. Manipulation as aforesaid, may be simplified by having the control of certain of these valves compounded so that the operation may more nearly approach simplicity of control and any suitable well known means may be employed for this purpose. Furthermore, by arranging several reaction chambers in multiple the process may be made continuous and one group of chambers may be made alternately active with another group. The gases passing out will contain carbon dioxide and nitrogen along with small percentages of argon and other rare gases. The other

gases may then be separated from the nitrogen by any suitable well known means either chemical or physical, preferably the latter, which may be done by liquefaction to the proper temperature and pressure to remove these gases to the extent desired, any well known form of apparatus being employed for the purpose.

I claim:

1. The method of recovering nitrogen from mixtures containing N and CO which comprises burning said mixture in the presence of a limited supply of air to effect incomplete combustion only, passing the gases of combustion through refractory material to oxidize said gases, whereby said refractory material is reduced, regenerating a portion of said refractory material only, while keeping the remainder in a reduced condition, and thereafter maintaining the latter in its reduced condition.

2. The method of recovering nitrogen from mixtures containing the same which comprises burning said mixtures in the presence of a limited supply of air to effect incomplete combustion only, passing the gases of combustion through a heat exchanger, passing the heated gases through refractory material to oxidize said gases, whereby said refractory material is reduced, regenerating a portion of said refractory material only, while keeping the remainder in a reduced condition, and thereafter maintaining the latter in its reduced condition.

3. The method of recovering nitrogen from mixtures containing the same which comprises burning said mixture in the presence of a limited supply of air to effect incomplete combustion only, passing the gases of combustion through a heat exchanger, passing the heated gases through a body of refractory material of substantial length, to oxidize said gases whereby said refractory material is reduced, throughout substantially its entire length, regenerating a portion of said refractory material substantially midway of the body while maintaining the portion at the entrance of the gases in its reduced condition, and maintaining the last mentioned portion in its reduced condition throughout the rest of the time the apparatus is in operation.

4. The method of recovering nitrogen from mixtures containing CO and N which comprises burning said mixture in the presence of a limited supply of air to effect incomplete combustion only, passing the gases of combustion through a heat exchanger, passing the heated gases through a body of refractory material to oxidize said gases, and so conducting the operation that the oxidation of the gases and simultaneous reduction of the gases is substantially complete a short distance from the end of the body, regenerating a portion of said refrac-

tory material substantially midway of the body while maintaining the portion at the entrance of the gases in its reduced condition, and maintaining the last mentioned portion in its reduced condition throughout the rest of the time the apparatus is in operation.

5. In a process of the character described, the steps of reducing a refractory body throughout substantially its length by the passage therethrough of the gases to be treated, regenerating a portion of the reduced material, and maintaining the remainder in its reduced condition during the remainder of the passage of gases therethrough.

6. In an apparatus for recovering N from gaseous mixtures a combustion chamber, means for introducing regulated quantities of the mixture and air to the combustion chamber, means for burning the mixture in said chamber, a heat exchanger in said combustion chamber, a tube of refractory oxidizing material in said combustion chamber extending transversely therethrough, means for introducing the gases of combustion into said tube, means in said tube for disposing of excess oxygen which may enter, means for passing off the mixture when treatment is complete, and means for regenerating a portion of said refractory material which has been reduced by passage therethrough of the gases.

7. In an apparatus for recovering N from gaseous mixtures a combustion chamber, means for introducing regulated quantities

of the mixture and air to the combustion chamber, means for burning the mixture in said chamber, a heat exchanger in said combustion chamber, a tube of refractory oxidizing material in said combustion chamber extending transversely therethrough, means for introducing the gases of combustion into said tube, means in said tube for disposing of excess oxygen which may enter, means for freeing the gases of all traces of carbon monoxide, and means for regenerating a portion of said refractory material which has been reduced by passage therethrough of the gases.

8. An apparatus for use in the separation of nitrogen from a mixture of nitrogen and carbon monoxide, comprising a combustion chamber for burning the mixture, means for introducing regulated quantities of the mixture and air to the combustion chamber, a tubular chamber extending transversely through the combustion chamber, through which tubular chamber the gaseous products of combustion are conducted from the combustion chamber, finely divided metal in the first portion of the length of the tubular chamber and a metallic oxide in the remaining portion of the tubular chamber, and means for supplying air to the second portion of said tubular chamber to reoxidize the metallic oxide when it has become reduced.

In testimony whereof I hereunto affix my signature.

FERDINAND A. RUDOLF.
